(57) **CLAIM**

The ornamental design for a shoe sole, as shown and described.

DESCRIPTION

FIG. 1 is a perspective view;
FIG. 2 is a front elevational view;
FIG. 3 is a rear elevational view;
FIG. 4 is a left side elevational view;
FIG. 5 is a right side elevational view;
FIG. 6 is a top plan view; and,
FIG. 7 is a bottom plan view.

The broken lines showing a shoe upper throughout the views illustrates environmental subject matter which forms no part of the claimed design.
